(57) **CLAIM**

The ornamental design for a bug guard for beverage can, as shown and described.

DESCRIPTION

FIG. 1 is a front elevational view of a bug guard for beverage can showing my new design;

FIG. 2 is a rear elevational view thereof;

FIG. 3 is a top plan view thereof;

FIG. 4 is a bottom plan view thereof; and,

FIG. 5 is an isometric view thereof.

The broken lines in the drawings depict environmental subject matter only and form no part of the claimed design.
